[57] CLAIM

The ornamental design for a pre-assembled pallet-based bulk food display with divider and packages, as shown and described.

DESCRIPTION

FIG. 1 is a perspective view of the pre-assembled pallet-based bulk food display with divider and packages;

FIG. 2 is a front elevation thereof, the back view being a mirror image;

FIG. 3 is a side elevation view thereof, the opposite side being a mirror image; and,

FIG. 4 is a under plan view thereof.
